UNITED STATES PATENT OFFICE

HOWARD L. SMITH, OF LEXINGTON, KENTUCKY

TOBACCO PRESS

Application filed November 14, 1930. Serial No. 495,752.

This invention relates to a tobacco press and has for its primary object to provide, in a manner as hereinafter set forth, a device of such character which is thoroughly efficient in operation, and which is of exceedingly strong, simple and inexpensive construction.

A further object of the invention is to provide a tobacco press including a press board capable of movement in opposite directions longitudinally of a compression chamber to press tobacco in either end of the chamber, and further including automatically operating means for retaining the press board in pressing engagement with the tobacco pressed thereby after the release of the power for operating the press board.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the several views:

Figure 1 is a top plan of a tobacco press in accordance with this invention.

Figure 2 is a side elevation thereof.

Figure 3 is a vertical section therethrough taken on the line 3-3 of Figure 1.

Figure 4 is a vertical section therethrough taken on the line 4-4 of Figure 2.

Figure 5 is an enlarged fragmentary section taken at a point indicated by the line 5-5 of Figure 4.

Referring to the drawings in detail, the numeral 1 designates a plurality of vertically disposed supporting posts of angle iron construction, four of such posts being employed and constituting the corner posts of the press. Having end portions thereof fixedly secured to the posts 1 are a pair of side members 2 which extend in parallel spaced relation, and which preferably are formed of metal. At the ends of the side members 2 are a pair of end

members 3 which are preferably formed of metal and which are secured to the supporting posts 1. The end members 3 coact with the side members 2 to provide a compression chamber 4 which is open at its top and bottom. Secured to the outer faces of the side members 2 and extending longitudinally thereof are a pair of angle beams 5, the lower faces of which are substantially flush with the lower edges of the side members 2. Secured to the outer faces of the side members 2 and extending longitudinally thereof are a pair of angle beams 6, the upper faces of which are substantially flush with the upper edges of the side members 2.

Formed in the side members 2, in spaced relation to the upper edges thereof, are a pair of longitudinally extending slots 7 through which extends a shaft 8. The shaft 8 projects from both sides of the press and is provided at one end with a detachable power crank 9. The shaft 8 is journaled in a pair of bearings 10 which are disposed between and fixedly secured to a pair of vertically disposed, spaced plates 11 which constitute the press board of the press. The plates 11 are of appropriate width to fit snugly between the side plates 2 without binding, and extend above and below the upper and lower edges respectively of the side members. Carried by the plates 11 are a plurality of spacer elements which include relatively short rigid tubes 12 having bolts 13 extending therethrough and through the plates 11. The tubes 12 maintain the plates 11 in spaced relation, while the bolts 13 maintain the inner faces of the plates 11 in contact with the end faces of the tubes 12.

Secured to the upper and lower edges of the plates 11 are a pair of rigid, endless straps 14, the side portions 15 of which are vertically disposed in slightly spaced relation to the beams 5 and 6. Fixedly secured to the inner faces of the vertically disposed portions 15 on opposite sides of the press are a pair of angular guides 16 which are located in spaced relation to the bottoms of the vertically disposed portions 15, and end portions of which rest upon the upper faces of the beams 5. Fixedly secured to the inner faces of the vertically disposed portions 15 on opposite sides

of the press are similar angular guides 17 which are located in spaced relation to the upper ends of the vertically disposed portions 15, and end portions of which bear against the lower faces of the beams 6.

Fixedly mounted on the shaft 8, on opposite sides of the press, and outwardly of the side members 2, are a pair of cog wheels 18, the teeth of which project upwardly through openings 19 in the beams 6 to provide for a movement of the press board longitudinally of the chamber 4 upon a rotation of the shaft 8. Integrally connected with the straps 14, adjacent each side member 2, are a pair of pawls 20 which are adapted to extend at downward inclinations into engagement with the openings 19.

In the operation of the press, tobacco is suitably suspended to extend into the chamber 4 between the press board and one of the end members 3. The pawls 20, at the side of the press board adjacent the tobacco in the chamber are then swung upwardly about their pivots to a position such as indicated in dotted lines in Figure 3 and designated by the letter A. The shaft 8 is then rotated by means of the power crank 9 in a direction to move the press board towards the tobacco in the chamber by the engagement of the teeth of the cog wheels 18 with the openings 19 in the beams 6. As the press board moves longitudinally of the chamber, the pawls 20 at the opposite side of the press board from the tobacco in the chamber successively engage in the openings 19. When the press board has moved a sufficient distance to firmly press the tobacco between the same and one of the end members 3, the power for rotating the shaft 8 may be released, and any return movement of the press board will be prevented by the following pawls 20 which engage the walls of the openings 19 which are adjacent thereto and maintain the press board in pressing engagement with the pressed tobacco within the chamber.

It is thought that the many advantages of a tobacco press in accordance with this invention will be readily apparent, and although the preferred embodiment of the invention is as illustrated and described, it is to be understood that changes in the size, shape and arrangement of parts may be resorted to, so long as such changes fall within the scope of the invention as defined in the appended claims.

What I claim is:—

1. A press comprising, means to provide an elongated compression chamber adapted to receive therein a substance to be compressed and including a pair of side members, a press board movable longitudinally of the chamber to compress the substance therein, a pair of spaced beams secured to the outer face of each side member and projecting horizontally therefrom, a shaft extending

transversely of the chamber and movable longitudinally thereof, said shaft being rotatably connected with the press board, means for rotating the shaft, said shaft and one of the beams of each pair having coacting means for moving the press board longitudinally of the chamber upon rotation of the shaft, a rigid strap secured to the press board and extending peripherally thereof, guide members secured to the strap for abutment with the beams secured to the side members, and coacting means on the shaft and one of the beams of each pair for automatically maintaining the press board in pressing engagement with the compressed substance. 70

2. A press comprising, means to provide an elongated compression chamber adapted to receive in either end portion thereof a substance to be compressed, said chamber including a pair of side members formed with longitudinally extending slots, a press board selectively movable in opposite directions longitudinally of the chamber to compress the substance therein, said press board including a pair of spaced plates, a plurality of spacer elements for securing the plates of the press board together in spaced relation, an endless rigid strap extending around the periphery of each plate of the press board and having side portions thereof disposed outwardly of said side members, a pair of beams secured to the outer face of each side member and projecting horizontally therefrom, a plurality of guide elements secured to said rigid straps for engagement with said beams, a shaft extending through the slots in the side members, said shaft being rotatably connected with the press board, means for rotating the shaft, coacting means on said shaft and one of the beams of each pair for moving the press board longitudinally of the chamber upon rotation of the shaft, and oppositely disposed pawls pivotally connected with said strap for engagement with the means on said last mentioned beams for maintaining the press board in pressing engagement with the compressed substance. 80

3. A press comprising, means to provide an elongated chamber adapted to receive therein a substance to be compressed, a press board movable longitudinally of the chamber to compress the substance therein, a rigid strap secured to the press board and having portions thereof extending along the outer faces of the side walls of the chamber transversely of such walls and in spaced relation thereto, and guide members secured to said strap and disposed between the same and the side walls of the chamber. 90

4. A press comprising, means to provide an elongated chamber adapted to receive therein a substance to be compressed, a press board movable longitudinally of the chamber to compress the substance therein, a rigid strap secured to the press board and having

portions thereof extending along the outer faces of the side walls of the chamber transversely of such walls and in spaced relation thereto, beams secured to the outer faces of said side walls and extending longitudinally of the chamber, and guide members secured to said strap and projecting inwardly into engagement with said beams.

5. A press comprising, means to provide
10 an elongated chamber adapted to receive
therein a substance to be compressed, a press
board movable longitudinally of the chamber
to compress the substance therein, and a rigid
15 strap secured to the press board and having
portions thereof extending along the outer
faces of the side walls of the chamber trans-
versely of such side walls.

In testimony whereof, I affix my signature
hereto.
